US0D1104650S

(12) United States Design Patent (10) Patent No.: US D1,104,650 S
(45) Date of Patent: * Dec. 9, 2025

(54) CONTAINER CARRIER

(71) Applicant: Pacific Market International, LLC,
Seattle, WA (US)

(72) Inventors: Jeffrey Charles Munie, Seattle, WA
(US); Vignesh Chari, Seattle, WA
(US); Graeme Wagoner, Seattle, WA
(US); Melissa Metrolis-Poole,
Richmond, TX (US)

(73) Assignee: Pacific Market International, LLC,
Seattle, WA (US)

() Term: 15 Years

(21) Appl. No.: 29/917,793

(22) Filed: Nov. 22, 2023

(51) LOC (15) Cl. 07-09

(52) U.S. Cl.

USPC D7/624.2
